(57) **CLAIM**

The ornamental design for a display screen with a dynamic computer-generated page loading feature for use with an address bar of a browser, as shown and described.

DESCRIPTION

FIG. 1 is a front view of a display screen with a dynamic computer-generated page loading feature for use with an address bar of a browser, under a first embodiment; FIG. 2 is a front view of a display screen with a dynamic computer-generated page loading feature for use with an address bar of a browser, under a second embodiment; and, FIG. 3 is a front view of a display screen with a dynamic computer-generated page loading feature for use with an address bar of a browser, under a third embodiment.

The broken lines shown in the drawings are for the purpose of illustrating a display screen of a computing device, text, and other images, and form no part of the claimed design.
